HERMANN KERGEL, OF DRESDEN, GERMANY, ASSIGNOR TO THE FIRM OF SACHSENWERK, LICHT-UND KRAFT-AKTIENGESELLSCHAFT, OF NIEDERSEDLITZ, NEAR DRESDEN, GERMANY

UNI OR MULTI POLAR OIL BREAK SWITCH

Application filed August 7, 1924, Serial No. 730,578, and in Germany October 11, 1923.

This invention relates to oil break electric switches and has for its object to provide an improved switch of this type in the form either of a unipolar or multipolar switch. 5
5 In oil break switches as heretofore constructed the pulleys, guide rollers and the like, carrying and guiding the rope of the apparatus for lowering the oil tanks are arranged outside the cover of the switch, or on 10 the traveling frame of the switch, whereby the ropes which also are situated outside are often exposed to damage and generally are in the way of relays, circuit breakers and the like, which are arranged on the switch. 15 Furthermore, short circuits may be caused by the rupture of the ropes, especially when said ropes are situated above the cover.

In the case of electric motor controllers it 20 has heretofore been proposed to provide pulleys under the controller cover but outside the casing to enable the casing, which may be filled with oil, to be lowered by means of ropes when it is desired to expose the contacts.

The improved oil break switch according 25 to the present invention is so constructed that the principal contours of the cover and oil tank of the switch have simple geometrical shapes completely symmetrical about the two main axes at right angles and the said contours differ from one another in such a manner that free spaces are left beneath the switch cover outside of the tank for the disposition of the pulleys or the like of the apparatus for lowering the tank. 30

The space necessary for inserting the winch 35 of the oil tank, the pulleys, ropes and the like can preferably be obtained, for instance, by providing a circular, rounded, or polygonal, oil tank and a square, polygonal, or rounded lid or cover to the switch.

The accompanying drawings illustrate an 40 example of the improved construction of the oil break switch according to the present invention in which

Figure 1 is a side elevation and partial section, the section being taken on the line A—B, Fig. 2,

Fig. 2 is a plan and partial cross section, 45 and

Fig. 3 is a view similar to Fig. 2 showing another form of the invention.

Referring to the drawings and particularly to Figs. 1 and 2, the oil tank is indicated at *f* and the cover therefor at *d*. The cover is preferably rectangular in plan and the oil tank is polygonal and adapted when raised to have its upper end fit within the cover. Because of the different configurations in 55 plan of the oil tank and cover, when the upper end of the oil tank lies within the cover there are provided spaces *g* between the corner portions of the oil tank and the adjacent inner portions of the cover. These spaces *g* are utilized for the pulleys and ropes employed for raising and lowering the oil tank. 60

In one corner of the cover there is a pulley *a* mounted on a shaft *h* which may be suitably journaled in the cover. This shaft *h* may be 70 operated exteriorly of the cover by means of a suitable crank *k* or otherwise. On the inner end of the pulley *a* the rope *e* is suitably coiled and extends downwardly therefrom and at its extremity is suitably connected to a 75 lug *i* extending from the oil tank for this purpose. On the outer end of this pulley *a* a rope *e*⁸ is suitably coiled. This rope *e*⁸ extends from the outer end of the pulley *a* through a tube or conduit *c* suitably connected to the cover for this purpose. This 80 rope *e*⁸ then passes over a pulley *b* mounted on a stub shaft *h*' suitably journaled in the cover *d* and a bracket *m*, or otherwise, and the extremity of the rope *e*⁸ is suitably connected to a lug *i*² extending from the oil tank for this purpose. 85

At the opposite end of the shaft *h* there is a pulley *a'*. A rope *e'* is coiled on the inner end of this pulley and passes from the same 90 and has its extremity suitably connected in a lug *i'* provided on the oil tank for this purpose. On the outer end of the pulley *a'* there is a rope *e*². This rope *e*² passes from the 95 outer end of the pulley *a'* through a tube or conduit *c'* similar to the tube *c* and then passes over a pulley *b'* on a stub shaft *h*² suitably mounted in the cover *d* and a bracket *m'*, or otherwise, and the extremity of the rope 100

*e*² is suitably connected in a lug *i*³ provided on the oil tank for this purpose.

By reference to Fig. 3 it will be seen that instead of making the oil tank polygonal in plan the same may be circular in plan and the construction of the other parts of the apparatus may be made the same in all respects as those hereinbefore described in connection with the form of the invention shown in Figs. 1 and 2. Obviously also the tubes or conduits *c* and *c'* through which certain of the ropes pass may be arranged on the interior of the cover by being cast integral therewith, or in any other manner.

15 I claim as my invention:

1. In an oil break switch, a tank, a cover therefor, the said tank and cover being of different configurations to provide pockets in predetermined positions exteriorly of the tank and interiorly of the cover when the tank is in position relatively to the cover, devices mounted within the said pockets and concealed therein for raising and lowering the tank relatively to the cover, and means also within the cover for protecting the said devices by preventing the upper portion of the tank from coming into contact therewith when in place within the cover, and for preventing said devices if broken from falling into the tank and causing short circuits therein.

2. In an oil break switch, a tank of predetermined configuration, a rectangular cover adapted to receive the upper portion of the tank and to thereby provide pockets between the exterior of the tank and the corners of the cover, devices mounted within the said pockets and concealed therein for raising and lowering the tank relatively to the cover, and means also within the cover for protecting the said devices by preventing the upper portion of the tank from coming into contact therewith when in place within the cover, and for preventing said devices if broken from falling into the tank and causing short circuits therein.

3. In an oil break switch, a rectangular cover, a tank the upper portion of which is adapted to be received in the cover and is of such a configuration as to provide pockets between the exterior of the tank and the corners of the cover, pulleys mounted in the said pockets, ropes passing over the said pulleys and connected at oppositely disposed parts of the tank, the said pulleys and ropes being enclosed within and concealed by the cover, whereby through the pulleys and ropes the tank may be raised and lowered relatively to the cover, and means also within the cover through which a rope passes for preventing the upper portion of the cover from contacting with the rope when the tank is raised so that its upper portion is in position within the cover, and for preventing said ropes if broken

from falling into the tank and causing short circuits therein.

4. In an oil break switch, a rectangular cover, a tank the upper portion of which is adapted to be received in the cover and is of such a configuration as to provide pockets between the exterior of the tank and the corners of the cover, pulleys mounted in the said pockets, ropes passing over the said pulleys and connected at oppositely disposed parts of the tank, the said pulleys and ropes being enclosed within and concealed by the cover, whereby through the pulleys and ropes the tank may be raised and lowered relatively to the cover, and a guide tube also within the cover and through which a rope passes to protect the rope by preventing the upper portion of the tank from contacting therewith when raised to position within the cover, and to prevent the ropes if broken from falling into the tank and causing short circuits therein.

In testimony, that I claim the foregoing as my invention, I have signed my name this 9th day of July, 1924.

HERMANN KERGEL.
